UNITED STATES PATENT OFFICE.

MITCHELL COHEN, OF CHICAGO, ILLINOIS, ASSIGNOR TO DE LEON BANDEAU COMPANY, OF ST. LOUIS, MISSOURI, A CORPORATION OF MISSOURI.

HATBAND.

1,297,103.

Specification of Letters Patent. Patented Mar. 11, 1919.

Application filed February 7, 1918. Serial No. 215,790.

To all whom it may concern:

Be it known that I, MITCHELL COHEN, a citizen of the United States, residing at the city of Chicago, county of Cook, and State 5 of Illinois, have invented a certain new and useful Improvement in Hatbands, of which the following is a specification, reference being had to the accompanying drawings, forming a part thereof.

10 This invention relates generally to headwear and, more particularly, to a certain new and useful improvement in hat-bands, the chief object of my present invention being to provide, as a new article of manufacture, a band of neat, pleasing, and attractive appearance and at a relatively low cost, which is self-adapting to hat-crowns of various shapes and sizes, and which, irrespective of the shape of the crown, will lie flat 15 and smooth throughout its length thereupon.

With the above and other objects in view, my invention resides in the provision of a hat-band having its ends spaced apart and joined by independent also spaced apart 20 elastic tapes, whereby the band is adapted not only to fit crowns of various sizes, but also the opposite longitudinal marginal portions of the band are independently adjustable to adapt the band to lie smoothly, 25 evenly, and tightly upon the hat-crown irrespective of the particular shape or incline of the crown; in the provision of a hat-band of the kind described having stiffening-stays at the band-ends for maintaining the elastic 30 members or tapes in proper spaced relation; in the provision of a hat-band of the kind described having a bow for concealing the elastic and stay-members and adding an attractive and pleasing finish to the band; and 35 in certain novel features of form, construction, arrangement, and combination of parts, all as will hereinafter be described and afterward pointed out in the claims.

In the accompanying drawings,

40 Figure 1 shows in elevation a band embodying my invention as applied to a hat having a tapering crown;

Fig. 2 shows the band as applied to a hat having a straight-side crown;

45 Fig. 3 is a fragmentary view of the band,

showing the normal relation of the band-ends and flexible or elastic tapes or members;

Fig. 4 is a view similar to Fig. 3, showing the relation of the band-ends and flexible tapes when the band is applied upon a tapering crown, as in Fig. 1;

Fig. 5 is a view similar to Figs. 3 and 4, showing the relation of the band-ends and flexible tapes when the band is applied upon a straight-side crown, as in Fig. 2;

Fig. 6 is a fragmentary inside face view of the band, showing the bow-casing and the band-ends and flexible tapes as applied to a tapering crown;

Fig. 7 is an enlarged detail elevation, partly in section, of a band-end, fragments of the flexible tapes, and a stay; and

Fig. 8 is a transverse sectional view through the band taken approximately on the line 8—8, Fig. 7, in the direction of the indicating-arrows.

Referring more particularly to the said drawings, in which like reference characters refer to like parts throughout the several views, A and B indicate hats of ordinary type, which in their specific constructions form no part of my present invention and which, as shown, may vary in the shape of their crowns and be properly fitted with bands constructed according to, and embodying my invention.

1 indicates the body-portion of my new band, which preferably consists of a single piece of suitable material, such as ribbon having its side margins finished. At each end of the band, its side margins are folded or turned over upon the body of the band to form hems 2. Both band-ends are also doubled or folded backwardly upon the body 90 of the band to form hems 3, which extend throughout the width of the band and which are disposed at right angles to the trend of the band. The hemmed ends of the band are suitably spaced apart, and between the 95 spaced ends of the band are placed a pair of elastic members or tapes 4—4, whose ends are disposed upon the hems 3 and preferably within the hems 2 and secured to the band by thread-stitches or the like, the hems 2 and 100

3 reinforcing the band at its ends and providing sufficient body for the proper securement of the tape-ends. It will be understood in this connection that the combined length 5 of band 1 and tapes 4, united as described, is somewhat less than the circumference of the particular hat-crowns with which the band is to be employed, so that some elongation of the band will be required in placing the 10 same in display position upon the hat-crown. Such elongation of the band, however, may be readily accomplished without distortion of the band, due to the elasticity of the tapes 4; and due also to the tapes 4, the band is 15 conveniently self-adjustable to neatly and snugly fit hat-crowns of various sizes.

In order to maintain the band-ends stretched taut to their full width and the elastic tapes 4 at the same time properly spaced apart, I provide stiffening-stays 5, 20 formed of strips of relatively stiff or rigid material, such as buckram, hair-cloth, or the like, inclosed within suitable finish-casings 6 covering the outer exposed faces of 25 the stiffening stays. These stays are of a length substantially equal to the width of the band-ends at the hems 2, the stays being secured or fixed in place along the ending hems 3 by stitching their casings 6 to the 30 ends of the band.

In a band constructed according to my invention, the independent spaced elastic tapes 4, secured between the ends of the body-portion 1 at the extreme outer edges 35 of the band and forming a continuity of the side margins of the body-portion 1, will hold the band throughout snugly, smoothly, and evenly flat against the crown irrespective 40 of the shape or scope of the crown. If the crown has straight sides, as in Fig. 2, the two tapes 4 will be stretched equally and produce like tension on each side margin of the body-portion 1, the pull of the tapes 4 being exerted on the full width of 45 the body-portion 1 through its end stiffening-stays 5, which tend or serve to keep or maintain the band extended to its full width throughout its length around the crown. If the crown has tapering or sloping 50 sides, as in Fig. 1, the tapes 4 will be stretched unequally, the upper tape sufficiently to hold the upper margin of the body-portion 1 smooth and taut throughout the circumference of the crown and the lower 55 tape, at a somewhat greater tension, holding the lower band-margin smooth and taut also throughout the circumference of the crown, the unequal pull of the tapes being again exerted on the body-portion 1 60 through the stays 5, which similarly serve to maintain the body-portion 1 fully extended throughout its width; and it may be added that the greater tension exerted on the lower 65 tape 4 produces increased pressure on the

crown at the lower margin of the body-portion 1, the band being thereby more securely held in place and prevented from climbing or slipping upwardly on or over the tapering or sloping crown. 70

As a neat, attractive band finish, I provide the band with a device such as the bow 7 having on its rear face a casing-strip 8, the bow 7 with its casing 8 being loosely disposed on the band and while surrounding 75 and concealing the ends of the body-portion 1, the tapes 4, and the stays 5, yet permitting free movements of the band-ends, the tapes, and the stays as required in the operative placement or application of the band upon a 80 hat-crown.

The bands as thus constructed are supplied to the dealer separate from the hats, and are displayed for inspection and selection 85 by the customer, and present a neat and finished appearance throughout, both inside and outside, and as thus displayed in their loose or separate condition, the ends of the band and the stays 5 will become more or less exposed by the stretching of the band or by 90 the bow becoming displaced in handling, and by the arrangement of the stays and applying the finish-casings to conceal the outer faces thereof, the band maintains a neat and finished appearance, not only on the out- 95 side but on the inside as well.

I am aware that minor changes in the form, construction, arrangement, and combination of the several parts of my new hat-band may be made and substituted for those 100 herein shown and described without departing from the nature and principle of my invention.

Having thus described my invention, what I claim and desire to secure by Letters 105 Patent is:

1. As an article of manufacture, a hat-band, comprising an inelastic body portion having its ends hemmed upon themselves and spaced apart, a pair of spaced elastic 110 members secured at their opposite ends to the hemmed spaced ends of the body portion and with their outer edges extending to the extreme longitudinal marginal edges of the body portion, to thereby exert tension 115 on the extreme marginal edges thereof, and stiffening stays secured to the edges of the spaced ends on the inside of the body portion and extending to the marginal edges 120 of the body portion and overlying and concealing the hem and the ends of the elastic members, to thereby distribute the tension of said elastic members throughout the entire body portion of the band.

2. As an article of manufacture, a hat- 125 band, comprising an inelastic body portion having its ends hemmed upon themselves and spaced apart, a pair of spaced elastic members secured at their opposite ends to the hemmed spaced ends of the body mem- 130

ber and with their outer edges extending to the extreme longitudinal marginal edges of the body member, to thereby exert tension on the extreme marginal edges thereof, and 5 stiffening stays provided with finish-casings covering the outer exposed faces thereof and secured to the edges of the spaced ends of

the body portion and extending to the marginal longitudinal edges of the body portion and overlying and concealing the hem 10 and the ends of the elastic members.

In testimony whereof, I have signed my name to this specification.

MITCHELL COHEN.
